ADJUSTABLE TABLE MOUNTING

Peter S. Hardy, Trumbull, Conn., assignor to Peerless Aluminum Foundry Co., Inc., Bridgeport, Conn., a corporation of Connecticut

Application June 26, 1957, Serial No. 668,145

2 Claims. (Cl. 248—285)

The present invention relates to an adjustable table mounting, and is particularly adapted for embodiment in a core draw apparatus adapted for attachment to a sand molder's work bench, for the purpose of applying vibrations to a packed core box to facilitate removal of the core therefrom preparatory to the subsequent baking of the core.

An object of the invention is to provide an adjustable table mounting whereby core draw apparatus may be mounted upon either side of the work bench, depending upon the requirements of the particular worker, also may be readily adjusted to dispose the core supporting table of the apparatus and the vibrator plate at any desired angular position about a vertical axis, and may be readily adjusted to positions at varying distances from the side of the work bench.

Other objects and advantages of the invention will become apparent from a consideration of the following detailed description taken in connection with the accompanying drawings wherein a satisfactory embodiment of the invention is shown. However, it will be understood that the invention is not limited to the details disclosed but includes all such variations and modifications as fall within the spirit of the invention and the scope of the appended claims.

In the drawings:

Fig. 1 is a front elevation of a core draw apparatus embodying the adjustable table mounting of the invention, the same being shown mounted upon the right hand side of a work bench indicated by dot-and-dash lines;

Fig. 2 is a top plan view of the horizontal table top partially broken away;

Fig. 3 is an end view as seen from the right in Fig. 1, and showing in dot-and-dash lines the mounting of a knee-operated valve or switch upon the apparatus;

Fig. 4 is a vertical sectional view taken along the line 4—4 of Fig. 1;

Fig. 5 is a bottom plan view of the table part of the apparatus;

Fig. 6 is a top plan view of the bracket part of the apparatus;

Fig. 7 is a top plan view of the adjusting lock part;

Fig. 8 is a side elevation of the lock part;

Fig. 9 is a bottom plan view thereof; and

Fig. 10 is a perspective view of the retaining lug member for the adjusting lock part.

Referring to the drawings the core draw apparatus, embodying the adjustable table mounting according to the illustrated exemplary embodiment of the invention, comprises a supporting bracket 10 comprising a transverse vertically disposed attaching portion 11 integrally formed with and extending at each side of a horizontally extending arm 12, right-angularly extending ears 13—13 being provided at the ends of the attaching portion 11. The attaching portion 11 is provided with suitable bolt-receiving holes 14 for its attachment by bolts 15 to the side 16 of a work bench, as indicated by the dot-and-dash lines in Fig. 1, and the ears 13 are provided with

2

holes 17 for the attachment by bolts 18 of a knee-operated valve or switch unit 19, as indicated by the dot-and-dash lines in Fig. 3. This unit is provided at the front of the work bench, and in the case of the bracket being mounted upon the right hand side of the work bench, as illustrated in Figs. 1 and 3, the valve or switch unit will be mounted upon the forwardly disposed ear 13. Thus, when the apparatus is mounted upon the left hand side of the work bench, the switch or valve unit will be mounted upon the opposite ear 13 which, in such case, will be disposed forwardly.

The arm 12 is of inverted U-shape in cross-section and includes a top wall 20 and a peripheral side wall 21, the top wall being provided with a longitudinally extending slot 22 defined by laterally spaced parallel longitudinally extending side rail portions of the top wall. Extending transversely to the slot at each side thereof, there are provided in the upper surface of the side rail portions of the top wall pairs of transversely aligned longitudinally spaced grooves 23.

The table part 24 is of generally rectangular shape and of reinforced grid formation for strength and lightness, and is provided at its upper side at its four corners with circular pockets 25 in which rubber cushion members 26 are seated for providing cushioning support for the table top, as will presently more fully appear. A vertical bolt receiving hole 27 is provided centrally through the table part, its upper end being disposed within a square bolt-head-receiving pocket 28 in the upper side 20 of the table part, and a circular band 29 of radial teeth, similar to a crown gear, being provided at the lower side of the table part in concentric surrounding relation to the lower end of the hole 27.

An adjusting lock part comprises a block member 30 having at the upper side a circular band 31 of radial teeth similar to the teeth 29 of the table part, and normally in interlocked meshed relation therewith, is provided centrally with a bolt receiving hole 32 in register with the bolt receiving hole 27 of the table part. At its under

40 side the lock part 30 is provided with a rectangular downwardly projecting boss 33, adapted to be slidably engaged within the slot 22 of the bracket arm 12, and transversely at each side of the boss there are provided a pair of transversely aligned rib projections 34—34 adapted to engage a transversely aligned pair of grooves 23 of the arm, the boss adapted through engagement in the slot to permit longitudinal adjustment therein, while at the same time preventing relative turning movement of the lock part, and the rib projections through engagement in the selected grooves fixing the position of longitudinal adjustment of the lock part upon the arm.

The downward projection of the boss 33 is substantially equal to one-half the thickness of the top wall 20 of the bracket arm, and a retaining lug member 35 having an upwardly projecting boss 36, similar in outline and projection to the boss 33, is engaged upwardly in the slot 22 and transversely extending flanges 37—37 of the lug member engage the under side of the wall 20 at each side of the slot. A bolt receiving hole 38 is provided in the lug member in register with the bolt holes 32 and 27, and a square-head clamping bolt 39 is engaged through the registering holes 27, 32 and 38 with the head of the bolt engaged in the pocket 28, a nut 40 being screwed upon the lower end of the bolt beneath the lug member.

65 It will be seen that upon loosening of the bolt the teeth 29 of the table part may be disengaged from the teeth 31 of the lock part to permit adjustment of the table part to any desired position of adjustment with a complete range of 360 degrees, and also the lock part, through disengagement of the ribs 34 from the grooves 23, may be adjusted to any desired position longitudinally in the slot 22 of the bracket arm, the desired adjusted position being

fixed through tightening of the clamping bolt. Thus it is possible to employ the same apparatus upon either side of the work bench, with the table part positioned forwardly in either case.

A core supporting horizontal table top 41 is mounted upon the table part, resting upon the cushion blocks 26 and being secured by bolts 42-42 engaged through holes 43-43 at the respective ends of the table part and retained by nuts 44 screwed upon the ends of the bolts.

The table part 24 is provided at its rearward side with a pair of right-angular post portions 45-45 which extend horizontally beneath the rearward edge of the table top 41, and vertically upwardly in back of the top and adjustably support a vibrator plate 46. The plate is of generally rectangular outline and is provided at its rearward side with a pair of rearwardly extending lugs 47-47 pivotally supported upon the respective posts 45-45 by means of bolts 48-48 for tilting movement of the plate about a central horizontal axis, the lugs each being disposed at the same side of the respective posts, i.e., the left hand side as seen in Fig. 2, to permit unimpeded vibration of the panel.

The angular position of the vibrator plate is fixed by a pair of thumb screws 49-49 screwed into threaded holes 50-50 in each of the posts 45-45 in equally spaced relation above and below the pivot axis of the respective bolts 48. The ends of the screws each have vibration dampening cushioned connection with the vibrator plate through respective engagement with metal discs 51 disposed in pockets 52 in the rearward side of the plate, each disc being resiliently supported by a cushion block 53 of rubber or the like disposed in its respective pocket beneath the metal disc. Thus while the screws maintain the position of adjustment of the plate, vibrations imparted to the plate are insulated from the table part.

Substantially centrally of the rearward side of the vibrator plate there is provided a rearwardly projecting lug 54, to which a vibration unit 55 is rigidly secured by a bolt 56. This unit may either be air operated as illustrated, in which case an air tube 57 extends to a knee-operated valve 19, or it may be an electric unit, in which case a conductor wire extends to a knee-operated switch 19.

Upon the face of the vibrator plate there is provided a series of vertical ribs 58 which are adapted to rigidly position a stop member 59 in selected positions of adjustment, the latter being provided upon its rearward side with a rib 60 which normally seats in a selected groove between a pair of the ribs 58. A clamping flange 61 at the lower end of the stop member extends beneath the vibrator plate and is provided with an inclined clamping surface 62 for clamping engagement with a bevelled surface 63 extending along the lower edge of the plate. A similar bevelled surface 64 extends along the upper edge of the plate and is adapted to be clampingly engaged by a thumb screw 65 engaged in a rearwardly extending flange 66 provided at the upper end of the stop member.

The clearance between the upper edge of the plate and the flange 66 is such with respect to the depth of the grooves between the ribs 58 that upon loosening the thumb screw 65 the stop member may be moved forwardly sufficiently to disengage the rib 60 from between the ribs 58, thus enabling the stop member to be freely moved to any desired position of adjustment. Tightening of the thumb screw forces the stop member both upwardly and inwardly and draws the rib 60 into the selected space between the ribs 58. Preferably the ribs 58 and 60 have tapered sides so that upon tightening of the thumb screw 65 they engage with a wedge fit to thus rigidly secure the stop member to the plate.

In operation, a supporting board together with a core

box having a sand core packed therein is placed by the molder upon the table top 41, and thereupon the core box is pressed against the vibrator plate 46 with one end of the core box held against the stop member 59. By pressing the knee-operated valve or switch 19 the vibration unit is actuated to impart vibrations to the plate, causing the core box supported upon the cushioned table top 41 to vibrate, thus loosening the core and enabling the operator to draw the core from the box by lifting the box along the vibrator plate, the core remaining on the supporting board upon the table top from which it can be transferred to the bake oven.

What is claimed is:

1. In an adjustable table mounting of the character described, a bracket part including an elongated supporting arm having a pair of laterally spaced parallel longitudinally extending side rail portions defining at their inner edges a longitudinally extending slot, attaching means at one end of said arm for attaching to the side of a work bench or the like, an adjusting lock part comprising a block member engaged at its under side with the upper side of said side rail portions having at its under side a downwardly projecting boss disposed in said slot and slidably and non-rotatably engaged with the inner edges of said side rail portions, and said block member having a vertical bolt-receiving hole extending from its upper side centrally through said boss, a horizontal table part at the upper side of said lock part having a vertical bolt-receiving hole co-axial with said hole of said block member, a retaining lug member engaged with the under side of said side rail portions having a vertical bolt-receiving hole co-axial with said hole of said block member, and a vertical clamping bolt engaged in said co-axial holes of said block member, said table part and said retaining lug member, said table part having at its lower side and said block member having at its upper side interengaging teeth in concentric surrounding relation to said bolt normally locking said table part against rotation relatively to said block member through the clamping action of said bolt, said interengaged teeth being disengageable through relative vertical movement of said table part upon release of said bolt to permit angular adjustment of said table part, said arm having at the upper side of said side rail portions a series of longitudinally spaced locking formations, and said block member having at its under side a locking formation normally interengaged with a selected locking formation of said arm and locking said block member against movement longitudinally of said arm through clamping action of said bolt, said interengaged formations being disengageable through relative vertical movement of said block member upon release of the clamping action of said bolt to permit longitudinal adjustment of said block member.

2. An adjustable table mounting according to claim 1, wherein said retaining lug has an upwardly projecting boss disposed in said slot and slidably and non-rotatably engaged with the inner edges of said side rail portions in vertically opposed relation to said boss of said block member.
